UNITED STATES PATENT OFFICE

IVAN RUBINSKY, OF BEIRUT, SYRIA

CALCULATING DEVICE

Application filed December 15, 1930, Serial No. 502,506, and in Syria January 20, 1930.

This invention relates to calculating devices, and more particularly to a computing tablet in the nature of a mechanical multiplying device wherein movable indicia members are employed to disclose, at a glance, the product obtained by multiplying any desired number by another number.

The primary object of the invention is to provide a device by which the user is enabled to reduce the process of multiplication to the simple addition of numbers, or rows of numbers and so to considerably facilitate the whole operation.

Other objects are to simplify and improve the construction of multiplying or calculating devices generally and to reduce the cost of manufacture thereof, so that a multiplying device may be manufactured at low cost and be thereby economically availed of by the public.

Other objects and advantages of the invention will be hereinafter specifically pointed out, or will become apparent, as the specification proceeds.

With the above indicated objects in view, the invention resides in certain novel constructions and combinations and arrangement of parts, clearly described in the following specification and fully illustrated in the accompanying drawings, which latter show embodiments of the invention as at present preferred.

In the drawings:

- Figure 1 is a perspective view of the device;
- Figure 2 is a top plan view of the obverse side of the device;
- Figure 3 is a top plan view of the reverse side of the device when turned end for end;
- Figure 4 is an obverse view of one of the indicia strips;
- Figure 5 is a reverse view of the indicia strip shown in Figure 4, when turned end for end with respect to Fig. 4;

- Figure 6 is a partial vertical sectional view on the line 6-6 of Figure 2, looking in the direction of the arrows;
- Figure 7 is a partial vertical sectional view on the line 7-7 of Figure 2, looking in the direction of the arrows;
- Figure 8 is a partial transverse sectional

view on the line 8-8 of Figure 2, looking in the direction of the arrows;

Figure 9 is a view similar to Figure 8, taken on the line 9-9 of Figure 2, and

Figure 10 is an elevation of a suitable pointer.

Referring more particularly to the drawings, the multiplication tablet shown in this instance, includes a casing A, which may be conveniently formed to include upper and lower covers B and C, respectively, separated at the top and both side edges by a suitable spacer D. The covers B and C may desirably be formed of relatively firm and durable card material, such, for instance, as fibre-board or heavy cardboard or other material; and the spacer D may consist of strips of cardboard or other material, or the same may be of one piece, in square U-shape.

The jacket or casing A thus consists of a hollow body, open at the bottom; and suitable means are employed to form a plurality of parallel, vertical guide slots E within the hollow body, as for instance, by providing a plurality of spacer strips F, these strips F also serving to hold the covers B and C together so that the tablet A, even though formed of relatively thin material will nevertheless be a substantially rigid unit.

The cover B includes a plurality of elongated parallel, vertical openings G, here termed multiplicand selector openings. These multiplicand selector openings may be laid out in any desired plurality; and alongside each opening G I arrange multiplicand indicia H which consist of vertical rows of numerals from 1 to 9, inclusive, arranged in inverse order, reading from the top downward.

It will be observed that the openings G are arranged centrally of the guide slots E. In the cover B, beneath the openings G and to the right thereof, I provide a horizontal row of small apertures J which are here termed multiplicand sight apertures.

Also, in the cover B, beneath the multiplicand sight apertures J, there is provided a plurality of horizontal rows of product sight windows K, the rows K in this instance have numeral designations 2, 3, 4 and 5,

which represent the multiplier. There may be any desired number of rows of windows K in the cover B, but to reduce the size of the tablet and increase its capacity, I provide in 5 the back cover C, additional horizontal rows of product sight windows L, here having numeral designations, 6, 7, 8 and 9 representing additional multipliers. The product sight windows K which are designated by the multipliers 2, 3 and 4 are in registration with the product sight windows L which are designated by the multipliers 6, 7 and 8.

The cover C also has a horizontal row of 15 multiplicand sight apertures M which correspond to the apertures J and are also designated by the numeral 1.

In both instances, the numeral 1 applied to the apertures J and M is to indicate the product obtained by multiplying a multiplicand by the multiplier 1; and the numeral designations 2 and 9 inclusive are multipliers, all as will be hereinafter more conveniently explained.

It will also be seen that the product sight 25 apertures O and P, at each end of each horizontal row, is one half the size of the intervening apertures L and K, the reason for which will also later appear.

The vertical multiplicand selector openings G, having the multiplicand indicia H, 30 indicate, reading from right to left, units, tens, hundreds, thousands, etc.; and means are provided whereby to indicate, at one or the other of the horizontal rows of sight windows K, the product obtained by multiplying any desired number selected from the vertical rows of multiplicand indicia H by the multiplier associated with the rows of sight windows K which displays the resultant 40 product.

In this instance I provide in each of the vertical slots E, a slideable flat indicia strip Q, the obverse side R of which is seen in Fig. 4, and the reverse side S in Fig. 5. Each of 45 the indicia strips Q has on its obverse side R, a group of numerals T, which correspond to the numerals H which represent the multiplicand indicia, the numerals T being arranged in the same order as the numerals H. 50 These numerals T are located in vertical alignment with the multiplicand sight apertures J and are hence normally invisible, except when brought into use whereupon the numerals T are adapted to be selectively displayed at the multiplicand sight openings J. The reverse side S of each strip is provided with a group of numerals U which correspond to the numerals T and are adapted to be displayed at the sight apertures M, the latter 60 being for convenience when using the reverse side of the tablet in connection with the multipliers 6 to 9 inclusive.

Each of the indicia strips is similarly constructed on both faces R and S with additional groups of product indicia W which are suc-

cessively arranged in correspondence with the multipliers 2, 3, 4, et seq., in accordance with arithmetical calculation, to indicate at the product sight windows K and L (and/or P or O) the product obtained by multiplication of a selected multiplicand by one or the other of the multipliers numbered from 2 to 9 inclusive. These latter groups of product indicia are arranged in two vertical columns, one column Wa indicating, in the "units" 70 strip Q, "units", and the other column Wb indicating, in the same strip, "tens" as derived from the multiplying operation. In the units strip Q the columns Wa are adapted to be displayed at the vertically aligned product sight apertures P which, as already stated, are one-half the size of the product sight apertures K; and the columns Wb are adapted to be displayed at the right hand side of the vertically aligned product sight apertures K. 75 Adjacent strips Q, representing "tens", "hundreds", etc., at their respective multiplicand indicia T, are adapted to display the columns Wa at the right hand side of the appropriate apertures K, and the columns Wb at the left 80 hand side of said apertures K. In the extreme left hand strip Q the numerals Wa are displayable at the left hand side of the appropriate apertures K and the numerals Wb, at the apertures O. It is clear from the above 85 that the apertures K overlap two adjacent strips Q.

Normally the strips Q lie in inoperative position so that no indicia are visible through the apertures J, K, O, P, L or M, the only 100 indicia visible being the multiplicand indicia H on the cover B. Means are provided to move the strips Q to display at the sight apertures J, K—O—P, M and L—O'—P', the product obtainable by multiplying any desired number, the digits of which have been selected from one or more of the multiplicand indicia H, by either of the multipliers designated 1 to 9 inclusive. In this instance each 105 of the strips Q is provided with a suitable mark, as for instance a small hole X opposite each of the multiplicand indicia numerals T, these holes X being accessible at the vertical openings G. A suitable pin or pointer Z is successively inserted in the hole opposite the 110 digit H desired to be selected from the multiplicand indicia, and the pin is pushed downward to the bottom of the opening G, in each case, the bottom of the opening G acting as a 115 limiting stop. The vertical groups of numerals T and W are so arranged that appropriate multiples of the multiplicand indicia H will be then displayed at the several rows of product sight openings opposite the multipliers numbered from 1 to 9, inclusive. 120

Thus, when it is desired to obtain the product by multiplying the multiplicand 111 by either of the multipliers, the three right hand strips designed for units, tens and hundreds are set, by means of the pin or pointer Z, to 125

indicate "111" at the apertures J and M, by moving each of the strips Q one step downward. The result at the different rows of multipliers will be as follows:

	Product	Multiplier
	111	1
	222	2
	333	3
	444	4
10	555	5
	666	6
	777	7
	888	8
15	999	9

A more practical illustrative example is shown in the drawings, however, wherein the multiplicand selected for illustration is 752. The result is seen somewhat differently in this instance, whenever the multiplier is greater than 1. For instance (and this is an important feature of the construction) whenever two digits (W_b and W_a) appear at the same window K, as in connection with the multiplier 2, wherein we find the result to be 1-41-0-4, the two digits appearing in the same window K are added together, so that the result, using the multiplicand 752 and the multiplier 2, is read 1-5-0-4 or 1504.

Similarly, for other multipliers, we see:

	Multiplier	Product indicia	Product
	3	2-11-5-6	2256
	4	2-82-0-8	3008
35	5	3-52-51-0	3760
	6	4-23-1-2	4512
	7	4-93-51-4	5264
	8	5-64-1-6	6016
	9	6-34-51-8	6768

It will be seen that in connection with the multipliers 4 and 7 and 8 we obtain product indicia in which certain of the digits appearing at one window K, when added together, exceed 9 so as to require two digits to express the result. In this case the "tens" digit, so far as the indicia appearing at each of the said windows K are concerned, is added to the product total of the digit or digits appearing at the next window K to the left, with the results as indicated in the table immediately above. The same procedure is observed regardless of the number of digits in the multiplicand.

Now, as a further development in the use of the apparatus, it is to be understood that while the device as shown and thus far described is equipped to utilize any desired multiplicand having up to eight digits, and multipliers from 1 to 9, the device is equally adapted for use with any multiplier having a plurality of digits. For instance, if the multiplicand 752 is to be multiplied by 864, we first select the product opposite the "units" of the multiplier, which is 4, and

write the same on a memorandum slip as follows:

3008 (see example above).

We then take the product opposite the "tens" of the multiplier, which is 6, and enter the same in proper relative "tens" position beneath the number 3008, as follows:

3008
4512
75

Similarly, we now select the product opposite the "hundreds" of the multiplier, which is 8, and enter the number in its "hundreds" position, beneath the other figures, so that the result appears as:

3008
4512
6016
85

The result 649728 is obtained by adding the three groups. There is thus practically no limit to the capacity of the device to multiply any multiplicand by any desired multiplier, accurately, conveniently and rapidly.

To re-set the device for a new multiplicand, it is simply necessary to hold the device vertically and press it down upon any flat surface so that all the strips Q pass entirely into their respective slots E.

It is to be understood that instead of providing spacer strips as shown at F, any desired spacing means may be employed to define the slots E, such for instance as by inserting wire staples or the like, in vertical rows, through the covers B and C; but the spacers F as shown provide a smooth running arrangement for the strips Q by positively defining the slots E.

What is claimed is:

1. A calculating device comprising a tablet formed with parallel guide slots and having windows in its face, the windows being arranged in parallel spaced rows, the uppermost row of windows being narrow and communicating each with one guide slot, the remaining rows of windows having the terminal windows thereof of the same width as the first said windows and communicating with the outermost guide slots, the intermediate windows in the remaining rows being double the width of the first said members and communicating each with two adjacent guide slots, and numeral bearing strips inserted in the guide slots and having the numerals thereof arranged at opposite longitudinal edges, and indicating means to permit adjustment of the strips in the guide slots according to a number to be multiplied, the rows of windows bearing digit indications of the multiplier.

2. A calculating device comprising a tablet formed with parallel guide slots and having windows in its face, the windows being arranged in parallel spaced rows, the upper-

most row of windows being narrow and communicating each with one guide slot, the remaining rows of windows having the terminal windows thereof of the same width as the first said windows and communicating with the outermost guide slots, the intermediate windows in the remaining rows being double the width of the first said members and communicating each with two adjacent 10 guide slots, and numeral bearing strips inserted in the guide slots and having the numerals thereof arranged at opposite longitudinal edges, and indicating means to permit adjustment of the strips in the guide 15 slots according to a number to be multiplied, the rows of windows bearing digit indications of the multiplier, the strip adjusting means consisting of slots communicating with the guide slots and opening onto the face of 20 the tablet, the latter having the digits arranged in consecutive order beside said slots, and the numeral bearing strips being formed with pointer receiving perforations spaced according to the numerals on said strips.

25 In testimony whereof I hereby affix my signature.

IVAN RUBINSKY.
